CONCEALED DRAWER FOR TABLES

Carl Frederick, Detroit, Mich.

Application November 4, 1946, Serial No. 707,627

2 Claims. (Cl. 312—246)

1

The invention relates to concealed drawers for tables and it is the object of the invention to obtain a construction in which the table has an unbroken side rail or depending skirt which, nevertheless, permits of concealing a drawer therewithin capable of being drawn outward therebeyond. To this end the invention consists in the construction as hereinafter set forth.

In the drawings:

Fig. 1 is a vertical cross-section through a table of my improved construction showing the drawer drawn outward therefrom;

Fig. 2 is a similar view with the drawer in concealed position; and

Fig. 3 is an enlarged section on line 3—3, Fig. 1;

Fig. 4 is a view similar to Fig. 1 showing a modified construction;

Fig. 5 is a cross-section on line 5—5, Fig. 4.

The table A may be of any suitable construction provided with depending side rails B which are continuous and may, if desired, be highly finished. C is a drawer normally stored beneath the table top within the space enclosed by the side rails B and completely concealed thereby. The drawer is supported by hangers or brackets D, which in turn engage runways E secured on the inside of opposite side rails and along which said hangers travel when the drawer is either withdrawn or replaced.

In order that the drawer may be withdrawn without interference with the side rails or skirt B, the hangers are attached to the inner portion of said drawer but are spaced sufficiently from each other to afford proper support. The front end C' of the drawer (in the direction in which the latter is withdrawn) is in stored position spaced from the corresponding side rail B' of the table. Also, the runways E are provided with parallel inclined portions E', E² down which the hangers travel during the initial outward movement of the drawer. The proportions are such that the drawer will be dropped a sufficient distance to clear the lower edge of the rail B' during a longitudinal travel equal to the space between the front C' and said rail. Consequently, during the further withdrawal of the drawer it will pass freely beneath said rail and outward a sufficient distance beyond the same to provide access to the contents. The runways E have in addition to the inclined portions E² horizontal portions E³ which extend to the rail B. These runways may be formed of channel bars which, considering the rail B' as the front of the table, are mounted on side rails B². They may, how-

2

ever, be spaced sufficiently inward from said side rails to avoid interference with the table legs F. To retain the drawer in stored position, the runways E have at their rear ends a slightly depressed portion E⁴ with a hump E⁵ between the same and the inclined portions E' and E². The hump is not, however, of sufficient height to interfere seriously with the passage of the hanger thereover.

While the hanger D may be of any suitable construction, I have specifically shown, and provided with ball bearing wheels, G which greatly reduces the friction during travel along the runways E.

In the modified construction shown in Figs. 4 and 5 the runways are suspended from the table top instead of being secured to a side rail thereof. These runways are also formed of flat bars instead of channel bars. As illustrated, the runway G¹⁰ has a portion G' at its rear end which is secured to the underside of the table top. A portion G² extending rearwardly and downwardly therefrom, a hump portion G³, an inclined portion G⁴, a horizontal portion G⁵ terminating in a return bent portion G⁶ and a portion G⁷ extending upward therefrom and secured to the underside of the table top by a portion G⁸. The runway H is similarly formed. However, to avoid interference between the two runways, which are in the same plane, the portion G⁷ of the runway G is laterally offset, as indicated at G⁹, to clear the inclined portion H' of the runway H. The hangers I are formed of plates secured to the side of the drawer C and having at their upper ends rollers J which are flanged to embrace the runway bars. This construction is exceedingly simple and inexpensive to manufacture and will serve the same purpose as the construction previously described.

What I claim as my invention is:

1. The combination with a table having a top and an imperforate rail or skirt depending therefrom, of a drawer normally stored beneath said top and concealed by said rail, the forward end of said drawer in its stored position being spaced from said rail, hangers for supporting said drawer secured to the rear portion thereof in spaced relation, rollers on said hangers and runways for said rollers each being formed of a bar having portions at its opposite ends secured to and depending from said table top, intermediate portion including an inclined portion and a horizontal extending portion, the depending portion of one runway being offset to clear the inclined portion of another runway.

2. The combination with a table having a top and an imperforate rail or skirt depending therefrom, of a drawer normally stored beneath said top and concealed by said rail, the forward end of said drawer in its stored position being spaced from said rail, hangers for supporting said drawer secured to the rear portion thereof in spaced relation, rollers on said hangers and runways for said rollers each being formed of a bar having portions at its opposite ends secured to and depending from said table top, intermediate portion including an inclined portion and a horizontal extending portion, the depending portion of one runway being offset to clear the inclined portion of another runway, and humps in said runways adjacent to the upper ends of the inclined portions thereof for holding said drawer in closed position.

CARL FREDERICK.
